UNITED STATES PATENT OFFICE

94,531

DESIGN FOR A DOOR

Kenneth E. Bemis, San Francisco, Calif.

Application June 11, 1934, Serial No. 52,138

Term of patent 14 years

To all whom it may concern:

Be it known that I, Kenneth E. Bemis, a citizen of the United States of America, residing at San Francisco, in the county of San Francisco and State of California, have invented a new, original, and ornamental Design for a Door, of which the following is a specification, reference being had to the accompanying drawing, forming part thereof.

The figure is a perspective view of a door, showing my new design.

The door is characterized by a polished metal

frame encompassing the light opening in the top portion of the door, and by a hand plate of horse-shoe form with interposed "T" forming a monogram "WT". The rear of the door is similar in appearance to the front with the exception of the omission of the dummy hinge bars and the hand plate.

I claim:

The ornamental design for a door, as shown and described.

In testimony whereof I affix my signature.

KENNETH E. BEMIS.
